RAZOR BLADE HOLDER

Michael Malecki, Brooklyn, N. Y.

Application September 11, 1941, Serial No. 410,396

5 Claims. (Cl. 30—333)

The invention relates to holders for razor blades and the like, and more particularly to devices for holding blades during the manual operation of honing or stropping them.

It is an object of the present invention to provide a device of the class described which is characterized by simplicity of construction, and which is easier to operate than devices heretofore known or used.

It has been proposed heretofore to clamp razor blades between a pair of members connected together by pins located in one member and extending through openings in the other member and so constructed that relative shifting in one direction causes them to clamp the razor blade therebetween by a wedging action. A serious disadvantage of such an arrangement is that it is frequently difficult to release the blade for removal by reason of the tightness with which the two clamping members are wedged together. In order to overcome this difficulty it previously has been considered necessary to provide special releasing levers for forcing the clamping members out of wedging engagement. It is an object of my invention to provide a holder which can easily be released without the use of such auxiliary levers.

Other objects and advantages of my invention will appear as the description proceeds. In the drawing, wherein I have illustrated a preferred embodiment of my invention,

Fig. 1 is a face view of my improved device showing the application of my invention to a holder for safety razor blades, the parts being shown in clamping position.

Fig. 2 is an enlarged detail sectional view taken as indicated at 2—2 in Fig. 1; and Fig. 3 is a view similar to Fig. 2 but showing the parts in the position which they occupy during the insertion or removal of the blade.

Fig. 4 is an enlarged transverse sectional view on the line 4—4 of Fig. 1.

My improved holder consists in its general arrangement of a pair of bars 10 and 11 which are connected together by suitable fastenings such as the screws 12 formed on or secured to the member 10 and extending through elongated openings or slots 13, 13 and 14 in the member 11. The members 10 and 11 are movable longitudinally relative to one another, and the connecting means are so constructed that relative shifting in one direction brings the members into position to clamp a razor blade 15 therebetween, as shown in Figs. 1 and 2. Shifting in the other direction brings the members 10 and 11 into the

relative positions shown in Fig. 3 to release the blade.

The slots 13 extend longitudinally of the bar 11 and are tapered longitudinally as shown at 16 in Fig. 1. Both the slots 13 and 14 are bevelled or tapered transversely of the bar 11 as shown at 17 in Figs. 2 and 3. The fastenings 12 may conveniently consist of ordinary flat headed machine screws having bevels 18 cooperating with the bevel 17 of the slots 13 and 14. The slot 14 has parallel sides, rather than being tapered longitudinally like the slots 13.

The bar 10 has a projection 19 formed thereon or secured thereto. In the embodiment illustrated, this projection 19 is formed by driving a pin into an aperture in the bar 10 so that it projects from the inner face of the bar. The projection 19 cooperates with an inclined surface 20 formed at the inside of the bar 11 whereby upon relative longitudinal movement of the two bars in one direction, they are forced apart at the blade-receiving end. This separating movement of the bars at the blade-receiving end is permitted by the co-action of the securing elements 12 and the longitudinally tapered slots 13, the securing elements being arranged to ride up and down the longitudinal taper of the bevelled slots upon relative longitudinal adjustment of the bars. However, the engagement between the parallel-sided slot 14 at the other end of the bar 11 and the cooperating securing element 12 is such that the bars are held together at this end for all positions of longitudinal adjustment thereof. Thus the bars are always held together at the righthand end as viewed in Fig. 1, while the cooperating engagements between the projection 19 and inclined surface 20, and between the securing elements 12 and the tapered slots 13 serve respectively to force the bars apart at the other end when moved from the position shown in Fig. 2 to the position shown in Fig. 3, and to force them together at that end when moved in the opposite direction. By holding the bars together at the outer end as described, the separating action is achieved with the use of a single projection 19 with its cooperating inclined surface 20.

Another important feature of my invention resides in so arranging the securing means that an end of one of the bars projects beyond the corresponding end of the other bar for all clamping positions of said bars. This is preferably accomplished by making one of the bars longer than the other, as shown in Fig. 1, wherein the bar 10 is longer than the bar 11 and projects beyond it at 21 when the bars are in clamping position.

With this construction, when it is desired to release the blade 15, it is merely necessary to tap the projecting end 21 of the longer bar 10 against a solid object, whereupon the inertia of the bar 11 will carry it into the position shown in Fig. 3, freeing the blade. Also, when a blade is inserted as shown in Fig. 3 and the bar 11 has been moved to the left, the end 22 of the bar 10 may be tapped against a solid object to bring the bar 11 into the clamping position shown in Fig. 2.

The bars may be constructed of standard metal shapes so that the device can be manufactured at very little cost. The preferred cross-sectional form is illustrated in Fig. 4, which view also shows the extreme compactness of the device. The exterior surfaces are curved, as at 23, so as to eliminate sharp corners, and to facilitate honing. The righthand end of the holder as viewed in Fig. 1 constitutes the handle portion of the device, and preferably is knurled or otherwise roughened so as to afford a gripping surface for the fingers while stropping.

It will be understood that while I have illustrated the device as used in holding a double edge razor blade, it can be employed with equal facility for holding single edge razor blades. Also, while the device is intended primarily for use in stropping or honing blades, it may also be used as a holder for blades for other purposes, as for a knife or scraper, etc. The terms and expressions which I have employed are used in a descriptive and not a limiting sense, and I have no intention of excluding such equivalents of the invention described, or of portions thereof, as fall within the purview of the claims.

I claim:

1. A device of the class described comprising a pair of bars movable longitudinally relative to one another, means for securing said bars together to clamp a razor blade between them upon relative longitudinal movement of the bars in one direction and to free the blade upon relative longitudinal movement in the other direction, an end of one of the bars projecting beyond the end of the other bar in all clamping positions of said bars.

2. A razor blade holder comprising a pair of bars, one of said bars having a longitudinally-extending longitudinal tapered bevel-edged slot near one end and one of said bars having a longitudinally-extending slot whose sides are equally

spaced along their length near the other end, securing means extending through said slots into the opposite bar, one of said bars provided with a longitudinally inclined surface at a point intermediate said slots, a projection on the other of said bars engaging said inclined surface whereby upon relative longitudinal movement of the two bars in one direction they are forced apart at the end provided with the tapered slot.

3. A razor blade holder comprising a pair of bars, one of said bars having a longitudinally-extending longitudinal tapered bevel-edged slot near one end and one of said bars having a longitudinally-extending slot whose sides are equally spaced along their length near the other end, securing means extending through said slots into the opposite bar, one of said bars provided with a longitudinally inclined surface at a point intermediate said slots, a projection on the other of said bars engaging said inclined surface whereby upon relative longitudinal movement of the two bars in one direction they are forced apart at the end provided with the tapered slot, and said slot of equally spaced sides and its cooperating securing means holding the bars together at the other end.

4. A razor blade holder comprising a pair of bars one of which has a plurality of longitudinal slots, at least one of said slots being tapered both transversely and longitudinally of the bar, securing elements on the other of said bars engaging said slots, the securing element which engages said tapered slot having a portion complementary to the transverse taper thereof riding up and down the longitudinal taper thereof upon relative longitudinal adjustment of the bars.

5. A razor blade holder comprising a pair of bars one of which has a plurality of longitudinal slots, at least one of said slots being tapered both transversely and longitudinally of the bar, securing elements on the other of said bars engaging said slots, the securing element which engages said tapered slot having a portion complementary to the transverse taper thereof riding up and down the longitudinal taper thereof upon relative longitudinal adjustment of the bars, an end of one of said bars projecting beyond the end of the other bar for all positions of relative longitudinal adjustment of the bars.

MICHAEL MALECKI.
